DISPLAY RACK

Elmer F. Carlson, Chicago, Ill.

Application April 16, 1952, Serial No. 19,353

Term of patent 7 years

(Cl. D80—9)

To all whom it may concern:

Be it known that I, Elmer F. Carlson, a citizen of the United States and a resident of Chicago, in the county of Cook and State of Illinois, have invented a new, original, and ornamental Design for Display Rack, of which the following is a specification, reference being had to the accompanying drawings, forming a part thereof.

Fig. 1 is a front perspective view of a display rack embodying my new design; and

Fig. 2 is a rear perspective view of the display rack shown in Fig. 1.

I claim:

The ornamental design for a display rack, as shown.

ELMER F. CARLSON.
